UNITED STATES PATENT OFFICE

2,602,286

WATERTIGHT WATCH

Werner Schmitz and Jakob Schneider,
Grenchen, SwitzerlandApplication December 11, 1946, Serial No. 715,440
In Switzerland April 26, 1946

3 Claims. (Cl. 58—90)

1

The present invention relates to water-tight watches and more particularly to means for making watertight an attachment for regulating the watch without removing the outer bottom of the watch case.

An object of the invention is the provision of a water-tight seal for a watch regulator attachment which can be manipulated outside of the outer bottom of the watch case. Various means may be employed for achieving this object. For instance, a pivot may be provided having a head forced by a spring against a packing provided between the pivot head and the bottom of the watch case. This pivot and the packing would be preferably sunk in a thicker part on the outer surface of the bottom and held in place by a star-shaped spring fixed to the end of the pivot and having a bent arm made to cooperate with the regulating lever.

The water-tight device may comprise a pin pivoted in the cock and having a head extending through the outer bottom of the watch case, a packing being provided to form a watch-tight joint. In this case, the pin would be fitted with a cam, acting, against the constraint of a spring, on the regulating lever.

As a further modification of the invention, the water-tight device may comprise a stopper screwed into the bottom, which closes an aperture through which the regulating mechanism of the movement of the watch can be reached.

The attached drawing represents, by way of example and to the extent necessary to make the description of the invention sufficiently clear, three embodiments of the water-tight means according to the present invention.

Figs. 1, 2 and 3 illustrate a first embodiment of the invention;

Fig. 1 shows a section along line I—I of Fig. 3 of a device according to the invention;

Fig. 2 is a fractional plan view;

Fig. 3 is a view of the regulator mechanism of the watch;

Fig. 4 is a part sectional view along the line IV—IV of Fig. 6 of a modified device according to the invention in condition for adjusting the regulator;

Fig. 5 is a sectional view of the outer bottom of the closed case of a watch equipped according to Figs. 4 and 6;

Fig. 6 is a plan view from above of the regulator mechanism shown in Fig. 4;

Fig. 7 is a view in section along the line VII—VII of Fig. 8, the latter being a plan view, with a part of the bottom broken away, of a

further modification of a water-tight device according to the invention;

Fig. 9 is a bottom view of the device according to Figs. 7 and 8.

Like parts are designated by like numerals in the different figures.

Referring to Figs. 1, 2 and 3, numeral 1 designates the bottom of a water-tight watch case; numeral 2 designates the regulator cock to which the device is attached, pin 3 being pivoted in the cock and having a slit at its outer end. It is embedded in a water-tight packing 15 extending through the bottom and lining the joint between the inside of the hole in the bottom and the cylindrical surface of the pin. The latter is provided with a cam 4 resting on the bridge and actuating the regulating lever 5 against the tension of a spring 6. The required regulation of the position of the lever is effected by turning the pin 3 with a screw-driver. The water-tight device consisting of the pin 3 and the packing 15 permits regulation of the watch through the bottom, i. e. without having to open the case. Because of the coordinated positions of the lever and slit in the pin head, the exact position of the lever can be determined from the outside, a graduated scale being provided on the outside of the bottom.

In the embodiment shown in Figs. 4—6 a counter-sunk partly threaded hole 8 is provided in the bottom 1, in which a stopper 14 is inserted, compressing a packing-ring 13 on a countersunk seat, when the watch is in use. This is shown in Fig. 5.

Should it be required to regulate the lever, all that has to be done is to unscrew the stopper 14 and to introduce a key 7 in its place, fitting over the screwhead 9 fixed in the bridge, the former serving as a pivot. The key comprises a collar 10 having a notch 11 accommodating the tail-end of the regulating lever 5. The pointer 12 indicates the position of notch 11 on a graduated scale concentric with the screw-head 9.

In the embodiment of the invention shown in Figs. 7, 8 and 9, the bottom of the case is designated by numeral 1, the cock by 2, and the lever by 5. Case member 1 has a hole for receiving shank 20 of a pivot member having a collar portion 21 and a square-head 22 for unrotatably supporting a star-shaped spring 23 forming the hub portion of an actuating member 26, which can be best seen from Fig. 9. Three radial arms 24 forming part of portion 23 are bent so as to bear against the bottom 1 of the watch-case, thus squeezing the packing 25 beneath the collar

portion 21 into a corresponding seat in the bottom, making the latter sufficiently water-tight. The end of arm 26 is bent oppositely to arms 23 and is provided with a slot 27 fitting over the tail-end of the regulating lever 5.

In this way, the device for actuating the watch regulator is permanently pressed to the bottom. It has the advantage of being entirely independent of the movement, and it remains permanently water-tight independently of the condition of the packing, barring, of course, destruction of the latter.

What we claim is:

1. A water-tight watch, comprising a regulator having an arm for setting it, a case member having an inside and an outside and separating said regulator from the outside, a pivot member extending through said case member and having a collar at the outside of said case member, a packing interposed between said collar and said case member, an actuating member engaging said arm and having a hub portion made fast on said pivot member inside of said case member, said hub portion comprising resilient means resting on the inside of said case member for forcing said collar against said case member and compressing said packing.

2. A water-tight watch, comprising a regulator having an arm for setting it, a case member having an inside and an outside and separating said regulator from the outside, a pivot member extending through said case member and having a collar at the outside of said case member, a packing interposed between said collar and said case member, an actuating member engaging said arm and having a hub portion made fast on said pivot member inside of said case member, said hub portion comprising resilient arms extending ra-

dially from said hub portion and slidably engaging the inside of said case member for forcing said collar against said case member and compressing said packing.

5. A water-tight watch, comprising a regulator having an arm for setting the regulator; a case member separating said arm from the outside; operating means comprising an actuating member disposed between said case member and said arm and engaging the latter, a pivot member un-rotatably connected with said actuating member and extending through said case member and having a collar portion, a packing interposed between said collar portion and said case member, and resilient means forming part of said actuating member and being interposed between said pivot member and said case member for forcing the former against the latter and compressing said packing.
